UNITED STATES PATENT OFFICE.

CHARLES J. AHRENFELDT, OF NEW YORK, N. Y.

DESIGN FOR A CUP.

SPECIFICATION forming part of Design No. 32,421, dated April 3, 1900.

Application filed January 8, 1900. Serial No. 791. Term of patent 7 years.

To all whom it may concern:

Be it known that I, CHARLES J. AHRENFELDT, a citizen of the United States, residing in the city of New York, county of New York, 5 and State of New York, have invented and produced a new and original Design for a Cup, of which the following is a specification, reference being had to the accompanying drawings, forming a part hereof, and like letters referring to like parts in each figure of the same.

In the said drawings, Figure 1 is a side view of a cup, showing my design. Fig. 2 is a bottom view of the same.

The base B of the cup is indented at intervals around its bottom edge, giving it a wave-like contour, and the upper edge or brim A is of smooth circular outline, slightly flared, and on the outside it is raised slightly above the surface of the body. Running from the 15 brim to the base are a series of vertical grooves

or indentations C, arranged in pairs and converging slightly as they approach the bottom to correspond to the decreasing diameter of the cup. On the outside of each groove near the top is the combined leaf and floral ornament D. Between the grooves of each pair is the ornament E, which consists of a harp-shaped figure combined with leaves and a bell-shaped figure beneath it. 25

The handle F is of irregular curved outline 30 and is decorated with scroll ornaments F'.

What I claim is—

The design for a cup substantially as herein shown and described.

Signed at New York, N. Y., this 28th day 35 of December, 1899.

CHARLES J. AHRENFELDT.

Witnesses:

M. V. DOERING,
HERMAN MEYER.
